UNITED STATES PATENT OFFICE.

FRANK McINTYRE, OF NEW YORK, N. Y., ASSIGNOR TO EAGLE PENCIL COMPANY, OF NEW YORK, N. Y.

DESIGN FOR A LEAD-PENCIL.

SPECIFICATION forming part of Design No. 37,431, dated May 16, 1905.

Application filed November 3, 1904. Serial No. 231,304. Term of patent 7 years.

To all whom it may concern:

Be it known that I, FRANK McINTYRE, of New York, county and State of New York, have invented a new, original, and ornamental Design for Lead-Pencils, of which the following is a specification, reference being had to the accompanying drawing, forming part thereof.

The figure is a perspective view of a lead-pencil, showing my new design.

What I claim as new herein, and desire to secure by Letters Patent, is—

The ornamental design for a lead-pencil as shown.

FRANK McINTYRE.
